(57) **CLAIM**

The ornamental design for a pluggable module, as shown and described.

DESCRIPTION

FIG. 1 is an end view of the first end of the pluggable module of the present invention;

FIG. 2 is a right side elevation view of the pluggable module of the present invention;

FIG. 3 is a top plan view of the pluggable module of the present invention;

FIG. 4 is a left side elevation view of the pluggable module of the present invention;

FIG. 5 is a bottom plan view of the pluggable module of the present invention;

FIG. 6 is a perspective view of the pluggable module of the present invention; and,

FIG. 7 as an end view of the second end of the pluggable module of the present invention.
